PACKAGE BINDING DEVICE

Joseph R. Burns, Millbourne, Pa.

Application October 8, 1935, Serial No. 44,018

29 Claims. (Cl. 100—31)

This invention relates to devices or implements useful in stores, factories, offices and elsewhere to bind packages of various kinds, including grouped articles like cut flowers or plants, sticks, pencils, cards, letters, etc.

Considered from the broadest aspect, my invention is directed toward enabling quick and effective binding of packages or groups of articles to be accomplished with strip binding such as plain or adhesive tape, or ribbon of paper, textiles and other material or relatively-soft pliable metal, without waste of the binding material. This aim I realize in practice, as hereinafter more fully disclosed, in a simple, inexpensive and reliable device having relatively movable members, as well as means automatically operative upon separation of said members after they have been brought together at one side of the package, to draw a length of the binding from a continuous supply source for envelopment of the package, and, upon being transposed relative to the package and brought together a second time, to close the binding about said package, sever the measured length, and superpose the ends thereof under pressure. With adhesive bindings, the pressure thus applied will serve to unite the ends of the binding. When relatively stiff ribbon of paper, textile fabric or pliable metal is used as a binding, the superposed ends may be secured by twisting them through rotative movement of the device before they are released. In the embodiments herein illustrated, the movable members have the form of inter-pivoted jaws with operating handles so that the device can be easily and conveniently manipulated in one hand while the package being bound is held in the other hand, or by its own movable or immovable environment.

I also aim to provide, in connection with a binding device having the above attributes, means whereby the extent of separation of the two opposing components or jaws can be regulated to predetermine, at each operation, measurement of the exact length of binding necessary for a package of a given size.

My invention is further directed toward provision of means automatically operative subsequent to the second bringing together of its opposing components or jaws, to secure the superposed ends of the binding with clinched bands of wire or staples in the absence of adhesive.

Still other objects and attendant advantages will appear from the following detailed description of the drawings, wherein Fig. I is a side elevation of a binding device or implement conveniently embodying my invention, portions being

broken out and shown in section to expose interior details which would otherwise be hidden.

Figs. II and III are fragmentary longitudinal sectional views of the device in the region of the pivotal connection between its opposing components or jaws.

Fig. IV is a fragmentary sectional view taken as indicated by the arrows IV—IV in Fig. III.

Figs. V and VI are fragmentary detail views taken as indicated respectively by the arrows V—V and VI—VI in Fig. I.

Fig. VII is a fragmentary longitudinal sectional view of the device in the region of the jaw ends, showing said jaws closed with the parts performing the first step in a binding operation.

Figs. VIII and IX are views like Fig. VII showing succeeding steps in the binding operation.

Fig. X is a fragmentary detail sectional view taken as indicated by the arrows X—X in Figs. IX and XI.

Fig. XI is a detail sectional view taken as indicated by the arrows XI—XI in Fig. X.

Fig. XII is a fragmentary detail section taken as indicated by the arrows XII—XII in Figs. IX and XI.

Fig. XIII is a view corresponding to Fig. IX but looking from the opposite side of the device as indicated by the arrows XIII—XIII in Fig. X.

Fig. XIV is a fragmentary detail view partly in elevation and partly in section taken as indicated by the arrows XIV—XIV in Fig. X.

Fig. XV is a fragmentary view in plan taken as indicated by the arrows XV—XV in Fig. XIV.

Fig. XVI is a fragmentary detail section taken as indicated by the arrows XVI—XVI in Fig. XIII.

Fig. XVII is a detail sectional view showing the package after having been bound with the device.

Fig. XVIII is a fragmentary sectional view corresponding to Fig. VII showing an alternative form of my binding device with means for forming securing bands from wire and applying them to the superposed ends of the binding.

Figs. XIX and XX are views like Fig. XVIII showing successive steps in the binding and banding operation.

Fig. XXI is a view corresponding to Fig. XVIII but looking from the opposite side of the device.

Figs. XXII and XXIII are detail views partly in elevation and partly in section taken respectively as indicated by the arrows XXII and XXIII in Fig. XVIII.

Fig. XXIV is a plan section taken as indicated by the arrows XXIV—XXIV in Fig. XVIII.

Fig. XXV is a view corresponding to Fig. XXIV

showing how the band is clinched about the ends of the binding.

Figs. XXVI—XXVIII are detail views showing the progressive steps in the formation and application of the securing bands.

Fig. XXIX is a view corresponding to Fig. VII showing still another alternative embodiment of my invention in which preformed staples are utilized to secure together the superposed ends of the binding.

Fig. XXX is a fragmentary view partly in elevation and partly in section taken as indicated by the arrows XXX—XXX in Fig. XXIX; and,

Fig. XXXI is a fragmentary detail sectional view showing how the ends of the staples are bent down upon the superposed ends of the binding.

From Fig. I of these illustrations, it will be observed that the package binding device of my invention comprises a pair of opposing components herein shown as having the form of hollow jaws 1 and 2 which are pivotally connected by axially-aligned screws 3 (Fig. IV), the jaw 2 being bowed as at 4, so that the device can be closed, as shown in dotted lines, about a package 5 exemplified as a bundle of plant stems or sticks. Below the pivot screws 3 the jaw 1 is provided with an integral operating handle 6; while the jaw 2 has an operating handle 7 which has capacity for limited independent pivotal movement about the screws 3 for a purpose hereinafter explained, said handle 7 having an upward prolongation or arm 8, see Figs. II and III. A leaf spring 9 riveted to the jaw 2 within the hollow thereof and engaging a lateral projection 10 on the arm 8 of the handle 7 serves to yieldingly hold said jaw and the handle 7 in the relation shown in full lines in Figs. I, II and III. Normally, the jaws 1 and 2 are yieldingly held open by a helical spring 11 in compression between the handles 6 and 7 immediately below the pivot screws 3, see Fig. I. The spring 11 surrounds a stem 12 which is pivotally connected at 13 to the handle 7 of the jaw 2 and which extends through an aperture 14 in the handle 6 of the jaw 1. By means of an adjusting nut 15 engaging a screw-thread on the outer end of the stem 12 and acting as a stop for the handle 6, it is obviously possible to regulate the extent of separation of the jaws 1 and 2.

Supported by the jaw 1 is a supply reel 17 for ribbon or tape 18 which is to be used to bind the package 5, said reel being free on a pin 19 passing through bearing apertures in spaced ears 20 on said jaw. The pin 19 has a head 21 at one end, and its other end is threaded for engagement by a winged nut 22, see Figs. I and V. Interposed between one side of the reel 17 and the contiguous ear 20 of the jaw 1, is a disk spring 23, the pressure of which can be regulated by adjusting the winged nut 22 so that frictional restraint is imposed against the free rotation of said reel. As a means for further restraining the reel 17, there is provided (Figs. I and VI) a detent 24 which is pivoted at 25 to a lug 26 on the jaw 1, and which has a tooth 27 to engage a circular series of holes 28 in one of the side disks of said reel. The detent 24 moreover has a projection 29, so that, when required as later on explained, its tooth 27 can be withdrawn from the reel 17 by pressure of the thumb of the hand employed in operating the device, in opposition to a leaf spring 30 to which said detent is subject.

At its swinging end, the jaw 1 has a hollow head 31 (Figs. VII to XIII) enclosing a drum 32 and

a pressure roller 33 of rubber or the like, which, as also later on explained, cooperates with said drum to feed a definite amount of the tape 18 outwardly through an opening 34 in the front end of said head. A guard 35 within the head 31 serves, in conjunction with a small idler roller 36, to direct the tape 18 to the opening 34. At diametrically opposite points on its periphery, the drum 32 is provided with a transverse line of laterally-separated roughened pads 37; and secured to one side of the drum 32 by means of a screw 38 with capacity for rotative adjustment about the drum axis 39 is a member 40 having diametric arms with lateral end portions 41 (Figs. XIV and XV) occupying peripheral recesses 42 in said drum. Transversely-spaced roughened pads 43 of the member 41 intermesh with the roughened pads 37 of the drum 32 as shown in Figs. XIV and XV. By virtue of this arrangement, pusher pads of regulatable width are had to coat with the roller 33 in advancing the tape 18 as aforesaid.

At the side opposite the member 40, the drum 32 is provided with ratchet teeth 44 for engagement by a spring pressed hook pawl 45 pivoted to an arm 46 free to oscillate about the axis 39 of said drum. As shown, the arm 46 has a link connection 47 with a slide rod 48 which extends down through the hollow of the jaw 1 and which is confined to longitudinal movement by upper 30 and lower guides 49 and 50 internally of said jaw, see Figs. II, III and XI. A tension spring 51 (Figs. II—IV) connected at one end to a fixed pin 52 on the jaw 1, and at the other end to a stud 53 on the slide rod 48, normally maintains 35 said rod in elevated position with a stop 54 thereon engaging the lower guide 50. Near its bottom end, the slide 48 has an aperture 55 adapted, when the jaws 1 and 2 are closed, to receive the end of a finger 56 pivotally connected at 57 within the hollow of the jaw 2, and having a lateral arm 58 with a pin 59 therein engaging a slot 60 at the end of the arm 8 of the handle 7. By additional pressure on the handle 7 after the jaws 1 and 2 are brought to the closed or dotted line 45 position of Fig. I, said handle may be moved to the dot-and-dash line position with the result that the finger 56 is swung downward through coaction of the slot 60 in the arm 8 with the pin 59 of said finger as far as permitted by a stop 61 50 on the jaw 1, the movement being in turn imparted to the slide 48 and through the latter and the link 47, to the hook pawl 45 so that the ratchet wheel 44 is turned in the direction of the arrow in Fig. IX. The parts are so proportioned, that through the arrangement just described, the drum 32 is rotated through a quadrant at each actuation, accidental displacement of said drum while in its rest positions being prevented by engagement of a spring detent 62 (Fig. XI) fixed to one 60 side of the head 31, with circumferential notches 63 of a collar 64 fast on the drum axis 39.

Measured lengths of the tape 18 are cut from the supply on the reel 17 by a knife blade 65 with bosses 66 (Figs. XI and XII) guided for vertical reciprocation on a pair of fixed rods 67, said blade having a shearing action with the upper edge of the opening 34 through which the end of the tape 18 is projected. Projecting from the ratchet side of the drum 32 is a pair of diametrically positioned studs 68, which, as said drum is rotated, successively coat with a lateral projection 69 on one of the bosses 66 to effect upward shearing movements of the knife blade 65 in opposition to a tension spring 70.

The drum 32 and roller 33 are accessible for convenience of threading the tape 18 initially through a snap-latched hinged door 71 at the back of the head 31. There is also a similar hinged door 72 at one side of the head 31 affording access to the small guide roller 36.

Like the jaw 1, the jaw 2 is provided at its swinging end with a hollow head 73 having an opening 74 in its front face, which opening, when the jaws 1, 2 are closed, registers with the opening 34 in the head 31 of the jaw 1, as shown in Fig. VII. Housed within the head 73 is a clip 75 comprising a fixed member 76 secured to the front wall of said head directly above the opening 74, and a movable member 77 which is pivotally connected with the fixed member 76 by an axis pin 78. A torsion spring 79 (Fig. XVI) coiled about the axis pin 78 tends to urge the clip member 77 toward the fixed member 76 to grip the end 20 of the tape 18. At its forward end the movable member 77 of the clip 75 has a pendant projection 80 lying in the path of a horizontal bolt 81 which, adjacent its forward end, has guidance in an aperture 82 in the front wall of the head 31 of the jaw 1 and at its rear end in a slide bearing 83 fixed within the head. A depending lug 85 of the bolt 81 is adapted to be engaged successively by lateral studs 86 projecting from the drum 32 at the side opposite that occupied 30 by the ratchet teeth 44, said studs being arranged in quadrant relation. During each actuation of the drum 32 the bolt 81 is projected outward of the head 31 through coaction of one of the pins 36 with the depending lug 85 of said bolt and 35 thrust through the opening 82 and a corresponding opening 87 in the head 73 of the jaw 2 into engagement with the projection 80 on the movable member 77 of the clip 75. Normally, the bolt 81 is held in retracted position within the head 31 through coaction of a detent spring 88 in said head with a shoulder 89 on the lug 85. Occupying a cutout 90 in the upper corner of the head 73 is a presser bar 91 which is supported by vertical arms 92 (Fig. VIII) of a U-shaped 45 spring member 93 within the head 73, said spring being secured at its bottom by a rivet 94 and being steadied by lugs 95 secured to the outer wall of the head 73.

The operation of the device is as follows. With the jaws 1 and 2 open and the handles 6 and 7 grasped in the right hand, the device is moved forward relative to the package 5 which is to be bound and the jaws thereupon closed as shown in dotted lines in Fig. I. With this accomplished, the handle 7, by exertion of additional pressure thereon is moved from the dotted line position to the dot-and-dash line position of Fig. I with the result that through the movement imparted as a consequence to the finger 56 (which was engaged with the aperture 55 in the slide rod 48 during closure of the jaws 1, 2) the slide rod 48 is lowered, and the drum 32 rotated through a quadrant by action of the pawl 45 on the ratchet teeth 44. Incident to such quarter rotation of the drum 32, the pads 37, 43 at the time lowermost thereon wipe past the roller 33 and carry the tape 18 along with them through a small distance with resultant projection of a corresponding length of said tape end beyond the opening 34 in the head 31 of the jaw 1. Concurrently with this quarter rotation of the drum 32, one of the studs 86 wipes the depending lug 85 on the bolt 81, thereby projecting the latter through the opening 82 in the head 31 and the registering opening 87 in the head 73 of the jaw 2 into engagement with

the projection 80 on the movable member 77 of the clip 75 in said head 73. Thus, as the end of the tape 18 is projected through the opening 34 of the head 31 and into the opening 74 of the head 73 of the jaw 2, the clip 75 is opened to receive it. Upon completion of the quarter rotation of the drum 32, the stud 86 passes beyond the top of the lug 85 on the bolt 81, whereupon the movable member 77 of the clip 75 is freed to the action of the spring 79 which immediately re-acts to move the member 77 to closed position to grip the end of the tape 18, this movement being attended by pushing of the bolt 81 back into the head 31 where it is re-engaged and held in its normal position by the spring detent 88. Pressure on the handles 6 and 7 is thereupon released, allowing the spring 11 to open the jaws 1 and 2 as far as permitted by the stop nut 16 on the stem 12 with the result that a definite length of the tape 18 is drawn from the reel 17. During the opening of the jaws 1 and 2 as just explained, the detent 24 is held away from the reel 17 by pressure of the thumb upon the projection 29 of said detent so that said reel is, at this time, restrained only by the frictional action of the spring washer 28. The device is next transposed to the front of the package 5, whereupon the two jaws 1, 2 are once more brought together as shown in Fig. IX, by pressure upon the handles 6 and 7. By additional pressure upon the handle 7, the latter is again moved from the dotted to the dot-and-dash line position of Fig. I and as a consequence, another quarter rotation is imparted to the drum 32. This latter movement of the drum 32 is ineffective insofar as feeding of the tape 18 is concerned, but it does result in the actuation by the succeeding stud 86 of the bolt 81 to open the clip 75 as before; and also in the actuation of the knife blade 66, to sever the tape 18 as a consequence of upward movement imparted to said knife by engagement of one of the two studs 68 on the drum 32 with the projection 69 on one of the guide bosses 66 of said knife blade. During the second closing of the jaws 1 and 2, the presser bar 91 causes the leading end of the tape 18 to be effectively pressed against the opposite end of said tape overlying the front face of the jaw 31 of the handle 1. As a consequence, the two ends of the tape 18 are effectively gripped. When tacky adhesive coated tape 18 is used, this pressure serves to insure adhesion of the superposed ends of the binder tape. When tape 18 of relatively stiff non-adhesive paper or soft metal or wire are used as a binding, the superposed ends may be twisted together as shown in Fig. XVII by rotative manipulation of the device before they are released. Here again, the pressure bar 91 is effective to firmly hold the two ends of the tape 18 and prevent them from slipping from between the jaws 31 and 73 during the twisting operation.

In the form of my invention illustrated in Figs. XVIII-XXVIII, additional means are provided for forming securing bands 96 (Figs. XXV and XXVIII) from wire 97 and clinching them over the meeting ends of the strip tape 18a as the latter is wrapped about the package 5a which is to be bound. As in the first described embodiment, a drum 32a within the head 31a on the jaw 1a, cooperates with a roller 33a to project the end of the tape 18a through the opening 34a when the two jaws 1a and 2a are closed for the first time during each binding operation, said drum having a pair of diametrically-opposite circumferential pads 43a which respectively deter-

mine the amount of tape 18a projected. The roller 33a is in this instance located above the drum 32a, and coacting with it is an idler roller 98 which assists in directing the tape 18a horizontally toward auxiliary guide rollers 99. After leaving the rollers 99, the tape finally passes over the small supporting roller 36a and out through the opening 34a in the front face of the head 31a as shown in Fig. XVIII. The wire 97 10 may be supplied from a frictionally restrained reel (not shown) on the jaw 1a, which reel may be generally like the one designated 17 and employed for the tape 18 in the first embodiment. From the supply reel the wire 97 passes alongside the tape 18a up through the hollow of the jaw 1a to an idler roller 100 within the head 31a, (see Fig. XXIV) which roller is free on the shaft of the roller 33a, and from thence said wire passes horizontally between cooperative feed rollers 101 and 102 whereof the former is adapted to be wiped by diametrically-opposite circumferential pads 103 on the drum 32a half way between the pads 43a. The circumferential extent of the pads 103 is such that, at each operation of the roller 101, the required length of wire 97 for a securing band 96 is fed forward. After leaving the feed rollers 101, 102, the wire 97 is directed by an idler roller 104 to a guide eye 105 fixed within the head 31a immediately inward of a frontal opening 106 therein above the opening 34a. When the jaws 1a and 2a are closed, the projecting end of the wire 97 encounters the concaved surface 107 of a recess in a block 76a which is secured within the opening 90a at the front face 35 of the head 73a of the jaw 2a, and which constitutes the fixed member of the tape clip 75a. By the concaved surface 107, the wire 97 is directed around the back of the superposed tape ends as shown in Fig. XXVI. Clinching of the bands 96 is effected as the wire 97 is cut by a pair of opposing fingers 108 with pendant cylindrical projections 109 at their free ends, said fingers being swingable inwards toward each other about fixed pivot pins 110 within an interval between the top wall of the head 73a and the block 76a. Confined by a guide 111 in the upper part of the jaw 73a is a slide 112 with forwardly projecting tongues 113 at opposite sides thereof which co-operate with the rear curved cam edges of the fingers 108 in concurrently swinging said fingers toward each other as shown in Fig. XXV in opposition to individually associated torsion springs 114 (Fig. XIX) to which they are subject. The slide 112 also has a forwardly projecting central tongue 115, for a purpose presently explained, and is actuated by an upward finger projection 116 on the movable member 77a of the tape clip 75a. The knife 65a is in this instance pivoted for swinging movement about a fixed center 117 and serves to cut both the tape 18a and the wire 97.

The operation of the modified form of device is as follows: As the jaws 1a, 2a are closed for the first time, and the rod 48a is actuated as in the first embodiment, and the drum 32a given a quarter rotation in the direction of the arrow in Fig. XVIII by action of the pawl 45a upon the ratchet wheel 44a. As a result, the tape 18a is projected into the opening 74a in the head 73a of the jaw 2a, the clip 75a being opened through outward movement of the bolt 81a by one of the studs 86a on the drum 32a. In Fig. XVIII, the movement of the drum 32a is just about to be completed with the active stud 86a leaving the lug on the plunger 81a so that the latter can be

returned to its normal retracted position within the head 31a to permit closure of the clip 75a under the action of the spring 78a when said stud has passed beyond the depending lug 85a of the bolt as shown in Fig. XX. The end of the tape 18a being now caught by the clip 75a, the jaws 1a and 2a are opened with attendant drawing out of a definite length of the tape 18a as already understood. This step is followed by moving the implement forward to wrap the tape 18a 10 part-way around the bundle 5a, whereupon the jaws 1a, 2a are again closed, with incidental actuation of the rod 48a once more and impartation by the pawl 45a of another quarter revolution to the drum 32a. By this last actuation of 15 the drum 32a, one of the pads 103 thereon wipes the roller 101 and thereby causes a definite length of the wire 97 to be projected outward of the head 31a in the manner previously described. During the forward feeding of the wire 97, the 20 concaved surface 107 of the block 76a in the head 73a causes said wire to be bent around the back of the two superposed portions of the tape 18a as shown in Fig. XXVI while the fingers 108 are moved toward each other as shown in Fig. 25 XXVII concurrently with the opening of the clip 75a and actuation of the knife 65a, to clinch the ends of the cut length of the wire 97 down upon the front of the superposed tape ends as shown in Fig. XXVIII. As the slide 112 moves forward 30 in the head 73a of the jaw 2a, the central tongue 115 thereof braces the wire 97 at the back as the cylindric projections 109 of the fingers 108 press the ends of the band 96 from the front, see Figs. XXV and XXVIII. As a consequence 35 of this cooperation of the tongue 115, the band 96 is clinched with positiveness, the movement of the fingers 108 being such that the tape ends 18a are slightly crushed as shown and thereby more effectively secured by the wire 97. All the 40 other elements in Figs. XVIII—XXVIII not specifically referred to but having their counterparts in the first described embodiment, are identified with the same reference numerals previously employed with addition in each instance however, of the letter "a" for the purposes of ready distinction.

In the modification of my invention shown in Figs. XXIX, XXX and XXXI, a supplemental means is provided for securing the superposed 50 ends of the tape band 18b by means of pre-formed staples 118. A stack of such staples 118, held together by shellac or varnish, is inserted into a vertical magazine 119 within the head 73b of the jaw 2b adjacent the inner face thereof, said magazine being accessible through an opening 120 in the top of said head protected by a slide cover 121. A pivoted latch 122 at the outside of the head 73b near the top, holds the cover 121 against displacement in closed position, see 55 Fig. XXIX. The stack of staples 118 is yieldingly urged upward by a follower 123 which is guided for movement upward in the magazine 119, and connected, by a cord 124, to a spring-influenced drum 125 mounted for free rotation 60 in fixed bearing brackets 126 within the head 73b. Incident to each operation of the device, the uppermost staple 118 in the stack is ejected through an opening 127 in the inner face of the head 73b adjacent its top, by a plunger 128 having guidance in a slideway 129. As a staple 118 is ejected, its ends are forced through the superposed portions of the binding tape 18b and encounter concaved surfaces 130 in the inner face 65 of the head 73b on the jaw 1b and are thereby 70 75

turned inwardly and clinched as shown in Fig. XXXI. The plunger 128 is normally held retracted in the head 73b with its rear end abutting the inner edge of the top opening 120, by a helical spring 131. The movable member 71b of the tape clip 75b in this instance has the form of a yoke, see Fig. XXX, and closes against the top edge 16b of the opening 14b in the head 73b, said edge 16b thus constituting the fixed member 5 of the clip 75b. Fixed to the shaft 18b of the clip 75b is the pendant projection or arm 80b which is engaged by a roller 132 at the end of the bolt 81b of the head 31b, and is thereby actuated to swing the movable member 71b of the clip 75 to 10 open position when the jaws 1b and 2b are closed. Free on the shaft 18b is a sleeve 133 with an integrally formed ratchet wheel 134 adapted to be rotated to the extent of one tooth during each actuation of the arm 80b, by a spring-pressed 15 hook pawl 135 on said arm. A toothed wheel 136, also integral with the sleeve 133, has cam teeth to coact with a downward lug 137 on the plunger 128 in operating the latter. It is to be 20 particularly noted that the wheel 136 has just half as many teeth as the ratchet wheel 134, so that the plunger 128 is actuated only upon the second closing of the jaws 1b, 2b for each binding 25 operation of the device. Accidental movements of the sleeve 133 are prevented by a spring-pressed 30 detent 138 which engages ratchet teeth 139 on one end of the sleeve 133. In all other respects, the construction and operation of the modification of Figs. XXIX-XXXI are exactly 35 the same as described in connection with the first two forms of my invention.

Having thus described my invention, I claim:

1. A package binding device comprising a pair of opposing jaw members adapted to be brought together relative to the package to be bound, one 40 of said members having an independently-movable portion; a rotatively-restrained manually-releasable means for continuous supply of binding medium on one of said members; clip means on the other member, operated by further inward 45 movement of the independently-movable member portion, means effective to eject the binding medium free end and to open and permit closure of the clip means for reception and grippage of said free end and, upon separation of the two 50 jaw members withdrawing a length of the binding medium corresponding to the extent of separation of said jaw members and sufficient to bind a package of predetermined size; a cutter device in one of the jaw members; and associated mechanism whereby the cutter is operated, upon drawing forward of the device relative to the package and a second bringing together of the jaw members, with a second inward movement of the independently-movable member portion to open 55 the clip means, and effect wrapping of the binding medium about the package, and severance of the previously jaw-spanning binding medium with the ends thereof superposed under pressure.

2. A package binding device as defined in claim 60 1 wherein the binding medium supply means is in the form of a rotary reel, a disk-spring engages one end of the reel to impose frictional restraint against its free rotation, and a manually-releasable catch has a tooth for engagement in holes 65 in one of the reel end walls for arresting said reel.

3. A package binding device as defined in claim 70 1 including a pivotal stem having its free end screw-threaded, and an adjusting nut on said free end whereby the extent of separation of the 75

two opposing members may be regulated for measurement of predetermined lengths of the binding.

4. A package binding device comprising a pair of opposing jaw members adapted to be brought together relative to the package to be bound, one of said members including an independently-movable handle-portion; a pivoted stem with a surrounding spring and an adjuster nut, tending to separate said members, whereby the extent of 10 such separation may be predetermined; a yieldingly-restrained supply means for continuous binding carried by one of said members, with an associated releasable catch normally arresting said means; means on the other of said members 15 to grip the free end of the binding so that, upon release of the members to expansive action a definite length of the binding, corresponding to the extent of separation of said members and the circumference of a package of predetermined 20 size, is withdrawn from the supply; means operated by further inward movement of the independently-actuable handle-portion to open the grip means and to eject the binding medium free 25 end into said grip means; and cutter means with associated mechanism whereby, upon transposal of the device relative to the package and bringing the jaw members together a second time, with a further inward movement of the independently-actuable handle-portion, the withdrawn length 30 of the binding, previously spanning the open jaw members, is closed about said package and severed, with the ends of such severed length superposed under pressure.

5. A package binding device comprising a pair 35 of opposing jaw members adapted to be brought together at one side of the package, one of said members including an independently-movable handle portion; a rotatively restrained and manually-releasable supply means for continuous binding 40 on one of said members; means operative as the jaw members are initially brought together, and the handle portion independently-moved inwards, to feed forwardly and project the end of the binding slightly beyond its carrying member; clip means on the other member actuated by the independently-movable handle portion after said members are initially-brought into contact to receive and grip the projected binding end 45 so that, upon the following separation of the two members a sufficient length of the binding corresponding to the extent of separation of the jaw members and the circumference of a package of predetermined size is held withdrawn from the supply, and upon transposal of the device relative 50 to the package, with a second bringing together of the members, such length of binding spanning the open jaw members is closed about said package, and means operative upon a further inward movement of the independently-movable handle 55 portion to sever the binding with the ends of such severed length superposed under pressure.

6. A package binding device comprising a pair of interpivoted jaws adapted to be closed about the package, one of said jaws having an independently-movable handle portion; a rotatively restrained and manually-releasable supply means for continuous binding strip on one of said jaws; means on the other jaw to grip the end of the binding so that, upon opening the jaws, a length 70 of binding strip, corresponding to the extent of separation of the jaws and with the circumference of a package of predetermined size, is withdrawn from the supply; means for opening the gripping means, projecting the binding strip free 75

- end into the gripping means, and operative upon transposal of the device relative to the package, and a second closure of the jaws, to effect closure of the spanning portion of the binding strip between said jaws about the package; and means whereby, upon a further inward movement of the independently-movable handle portion the binding strip is severed, with the ends of such severed length superposed under pressure.
7. A package binding device comprising a pair of interpivoted jaws adapted to be closed about the package, one of said jaws having an independently-movable handle-portion; a spring tending to separate the jaws; regulatable means whereby the extent of separation of the jaws may be determined; a yieldingly-restrained and manually-releasable supply means for continuous binding tape on one of the jaws; clip means on the other jaw, means for opening the clip means, and projecting the binding tape free end into position for grippage by the clip means, so that, upon release of the jaws to the action of the spring, a predetermined length of the binding tape, corresponding to the extent of separation of said jaws and the circumference of a package of predetermined size, is withdrawn from the supply; said last mentioned means being operative upon transposal of the device relative to the package, and closure of the jaws a second time, to close the jaw spanning length of the binding tape about the package and, upon a further inward independent movement of the handle portion to sever the binding tape, severed, with the ends of such length superposed under pressure.
8. A package binding device comprising a pair of interpivoted jaws adapted to be closed about the package which is to be bound, one of said jaws having an independently-movable handle-portion; a spring tending to open the jaws, a threaded stem extending through said spring and pivoted on one of the jaws and passing through an opening in the other jaw, a nut in threaded engagement with the protruding end of the stem whereby the extent of separation of the jaws may be regulated; a yieldingly-restrained and finger-releasable means for continuous supply of binding tape carried by one of the jaws; clip means on the other jaw; means for opening the clip means, and projecting the tape free end into position for grippage by the clip means so that, upon release of the jaws to the action of the spring, a predetermined length of the binding tape is withdrawn from the supply sufficient to encircle a package of predetermined size with a definite amount therebeyond to provide extending ends; said last mentioned means being operative upon transposal of the device relative to the package, and closure of the jaws a second time to wrap the length of the binding tape spanning the open jaws about the package, and upon a second further inward movement of the handle portion aforesaid to sever the binding tape, with the co-extending ends of such severed length superposed under pressure.
9. A package binding device comprising a pair of interpivoted jaws adapted to be closed about the package, one of said jaws having a rigid operating handle, and the other an operating handle connected to it with capacity for independent yielding movement; a coiled spring tending to separate the jaws with axial means for limiting their separation; a yieldingly-restrained manually-releasable supply means for continuous binding tape carried by one of the jaws; clip means carried by the other jaw; means, part of

which is rotary, operated upon initial bringing into contact of the interpivoted jaws, and further inward movement of the independently actuatable handle, to feed and slightly project forwardly the free end of the binding tape, and to open said clip means to receive and, when closed, grip the projected end of the binding tape, so that, upon re-opening of the jaws, a length of the tape sufficient to encircle and correspond with the circumference of the package of predetermined size is withdrawn from the supply; said device being operative upon transposal thereof relative to the package and a second closure of the jaws, to close the binding tape around the package, and additional means operative, upon a further inward movement of the independently-actuable handle, to sever the withdrawn length previously spanning the open jaws, with the ends of such severed length superposed under pressure.

10. A package binding device according to claim 9, wherein the means which is partially rotary includes an intermittently-rotated drum with circumferentially-spaced pressure pads, and a pressure roller to cooperate with the pads, a bolt actuatable by the drum to effect opening of the tape clip means, and interposed connections from the independently movable handle whereby the drum is actuated.

11. A package binding device according to claim 9, wherein the means which is partially rotary includes an intermittently-rotated drum with circumferentially-spaced pressure pads, and a pressure roller to cooperate with the pads, and a bolt operable by spaced studs on the drum effects opening of the tape clip means, means whereby the pads may be adjusted lengthwise to determine the amount of binding tape fed each time, and interposed connections from the independently-movable handle whereby the drum is actuated.

12. A package binding device according to claim 9, wherein the means which is partially rotary includes an intermittently-rotated drum with circumferentially-spaced pressure pads, a pressure roller which coacts with the pads, and interposed connections from the independently-movable handle which operate the drum; and means operated by said drum to actuate the clip means and the severing means.

13. A package binding device according to claim 9, wherein the means which is partially rotary includes an intermittently-rotated drum with circumferentially-spaced pressure pads, and a pressure roller to cooperate with the pads, and wherein the means for opening the clip means includes a projectable element operable by lateral circumferentially-spaced projections on the drum, and interposed connections from the independently-movable handle whereby the drum is actuated; and wherein the severing means includes a movable knife blade actuated by similar stud projections on the drum during non-feeding movements thereof.

14. A package binding device according to claim 9, wherein the means which is partially rotary includes an intermittently-rotated drum with circumferentially-spaced pressure pads, a pressure roller which cooperates with the pads, and interposed connections from the independently-movable handle which actuates the drum; the clip means has a movable member; and wherein the means for opening the clip-means comprises a bolt operated by studs on the drum.

15. A package binding device comprising a supply of continuous binding strip; means for

gripping the free end of said binding strip; reciprocative means for opening the gripping means; rotary means for projecting the strip free end into the open gripping means; a pair of opposing members adapted to be brought together relative to the package, said reciprocative and rotary means being parts of different opposing members, one of said members including an independently movable handle, connections whereby, when the members are brought together and the handle is further operated, the rotary means is operated and the reciprocative means is operated to first open and then release the gripping means, said members, on being separated, drawing out a spanning length of the binding strip which can, when the members are brought together again, be wrapped around a package of a predetermined size, said binding device including a cutter device and means which causes it to sever the binding strip when the members have been brought together a second time with the confronting ends of the strip in superposed relation, and when there has been further operation of the independently movable handle.

16. A package binding device according to claim 15, including means operative by the second "further operation" of the independently movable handle to form a securing band from wire, the strip cutter devices also severing the wire and, while said members are in contact, clinching the securing band about the intervening ends of the binding strip.

17. A package binding device according to claim 15, including means operative to force a pre-formed staple through the superposed confronting ends of the binding strip from one side thereof, and to bend the ends of such staple over upon said superposed strip ends at the other side thereof.

18. A package binding device in accordance with claim 1, including means for forming a securing band from wire by actuation of the independently-movable handle, the means which severs the binding strip also severing the wire, and for clinching said band about the superposed confronting ends of the binding strip after the second bringing together of the opposing jaw members.

19. A package binding device in accordance with claim 1, including means operative, subsequent to the second bringing together of the jaw members, to force a preformed staple through the superposed confronting ends of the strip of binding material from one side thereof, and to bend over the ends of said staple upon said superposed ends at the other side thereof.

20. A package binding device comprising a source of continuous binding medium; a spring-influenced device for gripping the free end of the binding medium; a slideable bolt for opening said gripping device; rotary means with a guard for projecting and directing the free end of the binding medium into the open gripping device; and a pair of interpivoted jaws, one of which includes said gripping device and the other of which include the bolt, and an independently-movable portion with actuator connections, said actuator connections operating, when the jaws have been brought together and the independently movable portion is operated, to cause the bolt to first open and then release the gripping means, and to cause the rotary means to project the binding medium, and said jaws operating, on being opened, to draw a length of the binding medium, corresponding to the extent of separation of said

jaws and the circumference of a package of pre-determined size from the supply source, and upon re-closing of the jaws to wrap the jaw spanning length of binding medium about the package, and a cutter operable by the independently-movable portion aforesaid to sever the wrapped length of binding medium while the ends of said medium are in contact with each other in superposed relation.

21. A package binding device according to claim 20, including a supply of wire, and means to form a securing band severed therefrom by the binding medium cutter, and to clinch such severed length about the superposed confronting ends of the binding medium.

22. A package binding device according to claim 20, including means to force a pre-formed staple through the superposed confronting ends of the withdrawn and severed strip of binding medium from one side thereof, and to bend the ends of the staple over upon said superposed ends at the other side thereof.

23. A package binding device in accordance with claim 6 including means for forming a securing band from wire, severed from supply by the binding strip cutter, and to clinch it about the superposed ends of the length of binding strip subsequent to a second closing of the interpivoted jaws.

24. A package binding device in accordance with claim 6 including means operative subsequent to a second closing of the interpivoted jaws, to force a pre-formed staple through the superposed ends of the binding strip from one side thereof, and to bend the ends of the staple over upon the superposed strip ends at the other side thereof.

25. A package binding device as defined in claim 9, including mechanism to form a securing band from wire severed from the supply by the means which severs the binding tape, and to clinch such severed length of wire about the superposed ends of the severed binding tape.

26. A package binding device as defined in claim 9, further including mechanism, also operated by the second "further inward movement" of the independently-movable handle to form a securing band from continuous wire and to clinch a severed length of it about the superposed ends of the binding tape, said mechanism including means on one jaw to project a definite length of continuous wire, means on the other jaw operative as the wire is projected, to round it about the superposed ends of the continuous binding tape from one side thereof, the tape severing means cutting off the rounded portion of the wire, and means also on the last mentioned jaw to bend the ends of the severed length of wire over upon said superposed tape ends at the other side thereof.

27. A package binding device as defined in claim 9 further including mechanism also operated by the second "further inward movement" of the independently-movable handle to form a securing band from continuous wire, and to clinch a length of it, cut off by the binding tape severing means, about the superposed ends of the package binding tape, said mechanism including directing-idler and cooperative feed-rolls in one of the interpivoted jaws, circumferentially-spaced pads on the rotary part cooperative with another of said rolls for intermittent rotation of the latter to project a definite length of the continuous wire, means on the other jaw

operative, as the wire is projected, to round the length of wire about the superposed ends of the continuous binding tape from one side, the rounded portion of the wire being then severed, and means also on the last mentioned jaw to clinch the ends of the severed length of wire over upon the superposed tape ends at the other side thereof.

28. A package binding device as defined in claim 9, including means, also operated by the independently-movable handle subsequent to a second closure of the jaws, to force a pre-formed staple through the superposed confronting ends of continuous binding tape from one side there-

of, and also to bend over the ends of the staple at the other side thereof.

29. A package binding device as defined in claim 15, including a magazine for pre-formed staples, a plunger on one of the opposing members, and means for operating said plunger by the second "further operation" of the independently movable handle, to force a staple from the magazine through the intervening superposed ends of the binding strip from one side, and by coaction with a surface on the other member, to bend the ends of the staple over upon the superposed strip ends at the other side thereof.

JOSEPH R. BURNS.
